[57]

ABSTRACT

A coupler including a knuckle having a convex gathering surface formed by an arc of fixed radius of which the arc approximates a portion of a spiral. The arcuate surface is generated so that in the open position of the knuckle the resultant force of the force normal to the face and the friction force at the point of contact along the length of the gathering surface is incapable of overcoming the resisting force at the pivot pin until the tip of the knuckle nose has passed a mating closed coupler.

KNUCKLE STRUCTURE FOR RAILWAY VEHICLE COUPLER

BACKGROUND AND SUMMARY OF THE INVENTION

The present invention relates to couplers and more particularly to an improved contour for a coupler knuckle to increase the gathering range of the coupler.

Coupling of railway cars is generally accomplished with the coupler knuckle on one car closed and the mating coupler knuckle on the other car open. Although under some circumstances both of the couplers may be open. At the same time, the track conditions or the couplers may be located such that the longitudinal axis of the mating couplers are not aligned. In order to achieve coupling it is necessary that the couplers be swung relative to each other during the initial contact so that the coupler axes are brought into axial alignment.

The extent to which the couplers may be axially misaligned and moved into coupling engagement is designated as the lateral gathering range. Heretofore, the standard gathering range required by the A.A.R. (American Association of Railroads) is about $1\frac{1}{4}$ inch. This limited gathering range has not eliminated passed couplers during coupling thereby causing coupler or car damage.

The alignment of the couplers into axial alignment occurs as a result of the force exerted at the knuckle faces during the initial and subsequent contact. This force must be sufficient to apply a moment with overcomes the sum of the coupler carrier friction moment and butt resisting moment of the shank of the coupler thereby to cause the couplers to swing about the butt end. However, the force at the engaging knuckle faces must be controlled to permit sliding of the knuckle faces as the couplers swing into alignment without causing the knuckle of the open coupler to close prematurely before it passes beyond the tip of the nose. Should the open knuckle close prematurely, the closed knuckle is prevented from entering into coupled engagement with the mating closed coupler.

By the present invention it is proposed to provide a coupler having an improved knuckle contour which achieves a greater gathering range than possible heretofore without premature closing of the open knuckle.

This is accomplished by forming the gathering face on the knuckle in the form of a convex surface of an arc of fixed radius which approximates a portion of a spiral. Preferably, the gathering face is contoured to approximate an arc of an equi-angular spiral so that the resultant force of the force of friction and the force normal at any point of contact along the entire length of the convex gathering surface is incapable of turning the knuckle from an open to a closed position until the tip of its nose has passed the tip of a mating coupler.

Further features will hereinafter appear.

BRIEF DESCRIPTION OF THE DRAWINGS

FIG. 1 is a top plan view of a coupler incorporating the improved knuckle structure of the present invention shown in coupling relationship with a coupler of conventional structure and shows the vector relationship of the forces for turning the couplers into longitudinal axial alignment.

FIG. 2 is a fragmentary view of a coupler knuckle incorporating the improved gathering face contour of the

present invention and showing in phantom the improved gathering surface and graphically illustrating the manner in which the theoretical spiral curve and actual curve is obtained and the resolution of the vector forces associated with curved surface on the knuckle.

DESCRIPTION OF THE PREFERRED EMBODIMENT

Referring now to the drawings there is shown a coupler 10 incorporating the structure of the present invention. The coupler 10 is shown in coupling position with a coupler 11 of substantially standard construction. The couplers 10 and 11 are of substantially identical construction differing only in the structure of knuckle 12 of the coupler 10 as more fully to be explained hereinafter.

The coupler 10 includes generally a coupler head 13 fixed to one end of a shank 14. The shank 14 is provided with a key slot 16 which receives the key (not shown) associated with the draft gear (not shown) mounted in the center sill (not shown) of the railway car on which the coupler 10 is mounted. The coupler 10 is horizontally swingable about its cylindrical butt 17 in the usual manner.

For convenience the corresponding components of the coupler 11 are identified with the same reference character, but with an *a* suffix. The coupler 11 includes a coupler head or housing 13a, a knuckle 12a, a shank 14a, a draft key pocket 16a and a butt 17a. The coupler 10 and coupler 11 are shown with the longitudinal axes 18 and 18a offset with respect to each other.

As is well known the knuckle 12 is attached to the knuckle side 19 of the housing 13 by means of a pivot pin 21 whereby the knuckle 12 is swingable between an open position and a closed position. Similarly, the knuckle 12a is swingable about a pivot pin 21a.

As mentioned above, the couplers 10 and 11 in FIG. 1 are shown offset or laterally displaced to illustrate the gathering range. When railway vehicles are approaching for coupling one or both of the knuckles may be open. Usually, however, coupling occurs with one knuckle open and the mating coupler closed. To achieve coupling, the couplers must be swung about the respective butt ends into longitudinal alignment. At the same time, the open knuckle must remain in the open position while sliding along the closed knuckle until the tips 25 and 25a of the noses of the two knuckles pass. After the tips 25 and 25a pass the open knuckle may be closed into coupling engagement with the mating closed coupler in the usual manner.

When the knuckles are both in the open position, at least one of the knuckles must remain open so that the tips of the noses similarly pass each other. It should be readily apparent that premature closing of the open knuckle when the other knuckle is closed results in failure to couple.

In accordance with the present invention the coupler knuckle 12 is provided with a convex gathering surface 22. The convex gathering surface 22 is located to lie in the path of movement of a buffering nose of a mating coupler.

The upper end of the convex surface 22 is located, as illustrated in FIG. 1, so that when contacted by a mating coupler the moment Rd , wherein R is the resultant force of the friction force fN and the force N normal to the point of contact, exceeds the sum of the carrier

friction moment Wb and the buff resisting moment Pa . Under these conditions swinging movement of the coupler about its butt end 17 is initiated. The surface 22 is curved so that the resultant force R as the knuckles slide produces a moment about the butt 17 which continues to swing the couplers into axial alignment.

The convex surface 22 is also curved so that the resultant force R at any point of contact along the curved surface 22 lies along a line which does not create an eccentric moment arm x relative to the turning axis c causing the open knuckle 12 to close prematurely before it passes the tip 25a of the closed knuckle. After the nose tips 25 and 25a pass, the knuckle 12 may turn to a closed position to couple with the closed knuckle 12a, in the usual manner.

The convex or curved gathering face 22 is generated along a curve so that the resultant force R at any point of contact along the length thereof lies on a line passing approximately the same distance from the pivot center c so as not to overcome the friction forces at the pivot pin 21. The frictional resistance about the pivot pin 21 may be represented as a vector by the friction circle FC as shown. The friction circle radius r^1 may be calculated by the formula $r^1 = fr$ wherein r is the radius of frictional contact about the pivot pin 21 and f is the coefficient of friction. From the foregoing it should be apparent that turning is prevented as long as $x \leq r^1$. This may be achieved by maintaining the resultant force along a line approximately tangent to the friction circle FC . Preferably, the eccentricity is maintained substantially equal to r^1 .

The curved surface achieving the desired relationship between x and r^1 is obtained by shaping the gathering face 22 as a spiral curve I as shown in phantom of FIG. 2 and having an equation $\rho = ke^{m\psi}$ wherein ρ is the radial distance from the center of pivot to any point on the gathering surface 22, ψ is the angle in radians from a reference line B—B, e is the value 2.71828 of the base of the natural system of logarithms; k is the magnitude of ρ when $\psi = 0$; m is the coefficient that establishes the rate of increase of the spiral radius; (m is also equal to the tangent of the angle λ between the radial direction of ρ and the direction of the normal force N at any point on the curve 22.)

The value of λ and m necessary to prevent premature closure of the knuckle is dependent on the friction angle ϕ at the points of contact of the coupling knuckle and the coefficient of friction f about the pivot pin 21. The parameters of a satisfactory curve between the points T and S as shown in FIG. 2 may thus be expressed by the relationship $\rho \sin(\phi - \lambda) \leq r^1$.

The curved surface 22 as shown is constructed so that one end T used as the reference for determining ψ lies in as close proximity as possible to the tip 25 of the knuckle nose without materially altering the basic geometry or strength characteristic of the existing knuckle structure. This assures that premature closing is prevented at a point immediately preceding the pass-

ing of nose tips 25 and 25a with a mating coupler. The curve I shown in phantom lines was generated from a value of coefficient of friction f which has been generally accepted as being present at the knuckle faces upon contact. It is to be noted that the resultant force R at any point along the curve 22, when the above relationships are maintained, lies along lines which are approximately tangent to the friction circle FC .

The curve I is constructed using the standard construction axis A—A of a standard knuckle and may be approximated by an arc which has a fixed radius Z to define the gathering surface 22. The center Y of the curved surface 22 having a fixed radius Z is located on the vicinity of the A—A construction axis above the center C as illustrated. Preferably the center Y of the fixed radius Z is angularly displaced clockwise of axis A—A, as viewed in FIG. 2, thereby to provide a curvature which achieves approximately the same force characteristics as the spiral curve I.

It should be understood that the arrangement described above constitutes the preferred embodiment and that many adaptations and modifications may be made without departing from the spirit of the invention.

I claim:

1. A railway vehicle coupler comprising a coupler housing, a knuckle, knuckle pivot means mounting said knuckle on said housing for movement about a pivot axis between an open position and a closed position, said knuckle having a nose tip, a convex gathering surface extending from a point closely adjacent to said nose tip, said gathering surface being curved such that the resultant force of the force normal to the surface and the friction force at any point of contact along the length of the gathering surface lies along a line which passes approximately a same selected distance from the pivot axis so as to be incapable of overcoming the frictional resistance at said pivot means and thereby prevent premature closing, said curved gathering surface including the arc of a spiral having the equation: $\rho = ke^{m\psi}$ wherein ρ is the radial distance from the pivot axis to any point on the gathering surface, ψ is the angle in radians from a reference point, e is the value of the logarithm to the base e , k is the magnitude of ρ when $\psi = 0$, m is equal to a tangent λ which is the angle between the radial direction of ρ and the line normal to the tangent of the curve, and said parameters of said curve are determined by the relationship $\rho(\phi - \lambda) \leq r^1$ wherein ϕ is the friction angle or arc tangent of the coefficient of friction at the point of contact with a mating coupler, and r^1 is the radius of a friction circle corresponding to the friction forces resisting turning of the knuckle about the pivot axis.

2. The invention as defined in claim 1 wherein said gathering surface is an arc having a fixed radius and lying substantially on said spiral curve.
